IGNITION COIL

Louis B. Ehrlich, Toledo, Ohio, assignor to The
Electric Auto-Lite Company, Toledo, Ohio, a
corporation of Ohio

Application December 24, 1932, Serial No. 648,774

14 Claims. (Cl. 175—361)

This invention relates to induction coils suitable for producing a high tension current, and particularly to coils suitable for use in ignition systems for internal combustion engines.

5 The invention has for an object to provide a structure wherein the elements of the ignition coil and circuit connections thereto are enclosed, forming a moist-proof unit.

The invention comprehends the provision of 10 means for decreasing possibility of current leakage between the high tension terminal of the secondary winding and the low tension terminals of the primary windings by increasing the surface path between said terminals.

15 The invention embraces the provision of a novel and efficient method of supporting and protecting the terminals of the coil windings and circuit connections thereto from moisture and foreign matter, insulating them from metallic 20 contact with other parts.

Another object of the invention is to provide improved means for connecting and securing the high tension cables to the high tension terminal, keeping these connections free 25 from moisture and foreign matter which would tend to cause break downs and short circuits.

Another object of the invention is to provide 30 an improved arrangement wherein certain of the coil winding terminals act as means for securing in place the means used for protecting the coil and terminals from moisture and foreign matter.

Further objects and advantages are within the 35 scope of this invention such as relate to the arrangement, operation and function of the related elements of the structure, to various details of construction and to combinations of parts, elements per se, and to economies of manufacture and numerous other features as will be 40 apparent from a consideration of the specification and drawing of certain forms of the invention, which may be preferred, in which:

Figure 1 is a top plan view of an ignition coil embodying my invention;

45 Figure 2 is a longitudinal sectional view taken substantially on the lines 1—1 of Figure 1;

Figure 3 is a detail view of the coil housing cover and coil terminals;

Figure 4 is an enlarged fragmentary sectional 50 view taken substantially on the lines 4—4 of Figure 1 showing the arrangement of the terminals and high tension cover;

Figure 5 is a top plan view of the coil housing with the high tension cover removed.

55 The invention may be included in any type of

high tension apparatus and for a practical application I have selected to illustrate the same as incorporated in an ignition coil suitable for use in internal combustion engines. It is to be understood that I do not wish to limit the invention to the particular embodiment illustrated, and that I also contemplate the use of my invention wherever the same may be found to be applicable.

Referring to the drawing, and particularly to Figure 2 in which the coil structure is illustrated,

the coil assembly comprises a metallic tubular member 15 closed at one end by a cover or base 16 interlocking one end of tubular member 15

60 forming an air-tight container or coil housing 17.

Within the coil housing 17 and adjacent to tubular member 15 is a plurality of sheet metal members or laminations 19, preferably of semi-

70 circular formation, these laminations being sup-

ported on base 16 and terminating slightly below

75 the extreme end of the casing 17. Concentric with the laminations 19 is a tube of insulating material 20, which tube serves as insulating means between the lamination 19 and the pri-

80 mary winding 22 of the ignition coil. Primary winding 22 is fixedly secured to an insulating

70 tube 24 resting on base 16. Within the insulat-

ing tube 24 is located a cylindrical porcelain

85 member 26 having a central recess 28 adapted to

receive a core of magnetic material 30. The

core of magnetic material 30 is preferably formed

80 of a plurality of laminations or strips compactly

assembled within a tubular member 32 of insu-

90 lating material, one end of which is received

within recess 28 and is supported by base 26.

Adjacent to the core 30 is the high tension wind-

95 ing comprising a plurality of layers of wire 34

properly separated by insulating material 36

which projects at each extremity of the layers

90 of wire 34. One of the ends of the insulating

material is in engagement with the porcelain

95 base 26.

The coil housing 17 is closed by a non-con-

ducting member or coil housing cover 40 prefer-

ably made of a moulded insulating compound

in which is imbedded a metallic ring 41 having

100 a flange portion 42 which snugly fits the outer

wall of the coil housing 17 and serves for secur-

ing cover 40 to the coil housing 17 in any suit-

105 able manner as by soldering, as illustrated at 43,

providing a hermetically closed container. Coil

housing cover 40 is provided at its inner end with

110 a downwardly extending annular flange or skirt

45 which surrounds one end of the magnetic

core structure 30, and contacts with the edges

of the insulating material separating the layers of wire of the high tension windings. Within the skirt portion 45 is located lead or connecting link 47 serving to connect the inner end of the 5 high tension winding to the high tension terminal or metallic threaded hollow member 50 supported by the coil housing cover 40 by passing through an opening in cover 40 and soldering lead 47 to terminal 50. Imbedded in coil housing 10 cover 40 is low tension terminal 52 to which is attached the outer end of the primary winding by means of a lead 53 which is located outside of the skirt portion 45 and which lead is surrounded by a tubular insulating member or insulating sleeve 54.

The terminals of the coil illustrating my invention to which the circuit connections are attached are similarly constructed and carried by coil cover 40, and for that reason only one terminal 20 is illustrated, and the method of connecting it to the coil winding is described in detail. Terminal 52 as particularly shown in Figure 4 is made of a good electrical conducting material, such as copper, and is preferably in the form of 25 a hollow threaded member having an enlarged portion 55 adjacent to the threaded portion 56, enlarged portion 55 is imbedded in the insulating compound of which cover 40 is made, forming raised portions of bosses 57. Cover 40, adjacent to enlarged hollow portion 55, is provided with an opening 58 through which passes lead 53 which projects through the hollow threaded portion 56 of contact 52. Solder is applied as 30 to 59 to close the terminal 52 and secure a good electrical connection between lead 53 and terminal 52.

The other end of the high tension winding, as well as the inner end of the primary or low tension winding, is connected to the terminal 61 imbedded in coil housing cover 40, by means of a 40 connecting link or lead 62 located outside of the skirt portion 45 and suitably insulated by means of a tubular insulating member 64. Terminal 61 is of similar construction to terminal 52 and lead 45 62 is secured to said terminal in a similar manner, as lead 53. The skirt portion 45 of the coil housing cover 40 forms a baffle and provides an obstruction for decreasing the possibility of current leakage between the high tension terminal 50 of the secondary winding and the low tension terminals 52 and 61 of the primary winding by increasing the surface path between said terminals.

The outer end of coil housing cover 40 is provided with a substantially U-shaped wall or projecting portion 65 which forms a separating baffle between the low tension terminals 52 and 61 surrounding the high tension terminal 50, and serves as means for decreasing the possibility of current leakage between the low tension terminal and the high tension terminals by increasing the surface path between the same. Within wall 65 and adjacent to terminal 50 is a semi-circular groove 67 which serves to accommodate the high tension insulating cable which connects to terminal 50 for carrying the high tension current to the distributor mechanism (not shown).

In order to completely enclose the high tension connections and keep the same free from moisture and foreign matter which tends to cause breakdown and short circuits, I provide an outer cover 70 made of a suitable insulating compound adapted to snugly fit the outer wall 72 of the coil housing cover 40. Cover 70 is

provided with openings 74 through which pass the low tension terminals 52 and 61 respectively. In order to hermetically seal the high tension connections I provide a rubber gasket 78 surrounding terminals 52 and 61 and these gaskets project into a recess 79 of the high tension cover 70. Cover 70 is kept tightly in place by nuts 80 coacting with the low tension terminals 52 and 61 and lock washers 82. A portion of the high tension cover 70 is provided with a semi-circular groove which coacts with semi-circular groove 67 and raised portion 69 of member 40 for compressing and supporting the high tension cable 83 attached to high tension terminal 50, and secured in place by nut 85 coacting with threaded portion of terminal 50. Groove 67 is provided with a ridge 69 which coacts with opening in the side wall of cover 70 for tightly gripping the insulating cable 83 when cable is secured to contact 50 and when the cover 70 is tightly urged in place through the tightening of nuts 80 coacting with threaded portion of terminals 52 and by providing a water tight enclosure, thus preventing dust, water and other foreign substances from fouling or otherwise injuring the coil connection. It can be seen that terminals 52 and 61 serve to receive the circuit connections or wires 86 and 87, and at the same time act as means for securing high tension cover 70 in place.

The coil structure is assembled within the coil housing 17 and before placing the insulating cover 40 any of the remaining cavities or spaces between the parts are filled with an insulating pitch or other insulating material (not shown), which is impervious to moisture and which serves as an additional means to prevent the derangement of the parts within the coil housing.

It is apparent that, within the scope of the invention modifications and different arrangements may be made other than is herein disclosed, and the present disclosure is illustrative merely, the invention comprehending all variations thereof.

What I claim is:—

1. An ignition coil including in combination a terminal; a non-conducting terminal supporting member; a non-conducting closure positioned adjacent to said first mentioned member providing an enclosure for said terminal; insulating projecting portions on said terminal supporting member adjacent said terminal; and means for fixedly retaining said closure in position to the terminal supporting member.

2. An ignition coil including in combination a core of magnetizable material; windings surrounding said core; said windings having terminals; a container for said core and windings; a cover for said container, said cover supporting the terminals of said windings; means cooperating with said cover for separating one terminal from the other terminals, and a closure enclosing said cooperating means and terminal.

3. An ignition coil including in combination a core of magnetizable material; high and low tension windings surrounding said core, said windings having terminals; a metallic container for said core and windings; a cover for said container, said cover supporting the terminals of said windings; means projecting in one side of said cover for separating one terminal from the other terminals, and a closure enclosing said projecting means and terminal.

4. An ignition coil including in combination a core of magnetizable material; high tension and

- low tension windings surrounding said core; a metallic container for said core and windings; a cover for said container, said cover supporting the terminals of said windings; means projecting from both sides of said cover for separating one terminal from the other terminals, and a closure enclosing said projecting means on one side of said cover and said terminal. 5
5. An ignition coil comprising a tubular casing containing primary and secondary windings, a non-conducting cover for the casing; primary and secondary terminals carried by the cover; a skirt provided on the cover extending within the coil casing; a central magnetizable core extending within the skirt; said secondary winding surrounding the core having leads separated by the wall of the skirt; said primary winding surrounding the secondary and having its leads connected with the primary terminals carried by the cover; a projection on the outside of said cover for separating the primary and secondary terminals; and a removable closure secured to said coil cover. 10
6. A moisture-proof terminal for ignition coils and the like, comprising in combination a non-conducting terminal supporting member provided with a groove adjacent said terminal, a projecting wall surrounding said terminal and said groove, a non-conducting cover removably supported on said first mentioned member providing an enclosure for said groove and terminal, and means for clamping the closure to the terminal supporting member. 15
7. An ignition coil comprising a tubular casing, containing primary and secondary windings, a non-conducting cover for the casing; a plurality of primary terminals and a secondary terminal carried by the cover; a skirt provided on the cover extending within the coil casing; a central magnetizable core extending within the skirt; said secondary winding surrounding the core having leads separated by the wall of the skirt; said primary winding surrounding the secondary and having its leads connected with the primary terminals; and a projection co-acting with said cover for separating the primary terminals and high tension terminal; and a removable closure secured to said coil cover. 20
8. A moisture-proof terminal arrangement for ignition coils and the like, comprising in combination a non-conducting terminal supporting member provided with a groove, a projecting wall surrounding said terminals adjacent said groove, a non-conducting closure removably supported on said first mentioned member providing an enclosure for said groove and terminals, and means for fixedly retaining the closure to the terminal supporting member. 25
9. An ignition coil including in combination a plurality of terminals; a non-conducting member for supporting said terminals; a non-conducting closure positioned adjacent to said mem- 30
- ber providing an enclosure for one of said terminals; and means coacting with one of said terminals for fixedly retaining said closure in position. 35
10. An ignition coil including in combination a plurality of terminals; a non-conducting member for supporting said terminals; a non-conducting closure positioned adjacent to said member; means projecting from said member for separating one terminal from the other terminal; and means coacting with one of said terminals for fixedly retaining said closure in position whereby one terminal and the projecting means adjacent thereto are enclosed by said closure. 40
11. An ignition coil including in combination, a housing containing primary and secondary windings; a member of non-conducting material serving as a cover for said housing and carrying a plurality of terminals for said windings; a second member supported by said first mentioned member forming a chamber for enclosing a terminal of said secondary winding; a wall within said chamber for separating said secondary terminal from the other terminals; and means co-acting with one of the other terminals for retaining said second member in position. 45
12. An ignition coil including in combination, a housing containing primary and secondary windings; a member of non-conducting material forming part of said housing supporting at least three terminals connected to said windings; a removable member co-acting with said first mentioned member to form a chamber; a wall within said chamber carried by one of said members for separating one of said terminals from the other of said terminals. 50
13. An ignition coil including in combination, a casing; a non-conducting cover for said casing; primary and secondary terminals carried by said cover; a removable closure secured to said cover by one of said terminals, said closure and cover forming a chamber; a groove formed on said cover adjacent to one of said terminals; and a projecting wall substantially dividing said chamber adjacent to said terminal and said groove for separating one of said terminals from the other said terminals. 55
14. An ignition coil including in combination, a casing; a non-conducting cover for said casing; primary and secondary terminals carried by said cover; a removable closure co-acting with said cover to form a chamber enclosing a secondary terminal, said removable cover being provided with openings through which a primary terminal projects, and with a lateral opening through which the circuit connection for the secondary terminal located within said chamber extends; and means co-acting with a projecting portion of a primary terminal for fixedly securing the closure in position. 60

LOUIS B. EHRLICH.
